TOY JACK

Elmer F. Morey, Riverside, Calif.

Application April 5, 1949, Serial No. 85,689

3 Claims. (Cl. 254—8)

1

This invention relates to a toy, and more particularly to a novel toy jack.

It is an object of this invention to provide a toy jack of the kind to be more particularly described hereinafter which may be formed of only those essential parts operatively connected together to form a toy operable substantially in the manner of a large, powerful lifting jack used for lifting automobiles and other heavy equipment.

Another object of this invention is to provide a toy jack of this kind which may be formed of any suitable material, the particular use or simulated use, determining the strength or size of the material from which it is to be made.

Yet another object of this invention is to provide a toy jack of this kind which may be readily formed and assembled at an economical cost to be distributed at a low price in the market of small toys and the like.

With the above and other objects in view, my invention consists in the arrangement, combination and details of construction disclosed in the drawings and specification, and then more particularly pointed out in the appended claims.

In the drawings:

Figure 1 is a side elevation of a toy jack constructed according to an embodiment of my invention;

Figure 2 is a top plan view thereof;

Figure 3 is an end elevation;

Figure 4 is a longitudinal section taken on the line 4—4 of Figure 2;

Figure 5 is a transverse section taken on the line 5—5 of Figure 1.

Referring to the drawings, the numeral 10 designates generally a toy jack constructed according to an embodiment of my invention. The jack 10 is formed to simulate the type of lifting jacks used for raising automobiles and other heavy equipment, and the jack 10, being a toy, may be formed of any suitable material, as metal, plastic or the like.

The jack 10 is formed of a base member 11 which is formed in the manner of a channel having a bottom wall 12, a rear wall 14, and a pair of side walls 15 and 16. The rear wall 14 extends perpendicularly from the extreme rear end of the bottom wall 12, while the side walls 15 and 16 extend forwardly from the side edges of the rear wall 14 and extends upwardly along the longitudinal side edges of the bottom wall 12. The side walls 15 and 16 are substantially triangular in configuration, being inclined downwardly and forwardly from the rear wall 14 and terminating at the extreme forward end of the

2

bottom wall 12. The top edges of the side walls 15 and 16 decline downwardly from the rear wall 14, being inclined along the length of the base member. The rear wall 14 is formed with an opening 17 intermediate the vertical height thereof through which a crank or screw element 18 is adapted to be rotatably engaged, in a manner to be more particularly described hereinafter.

The side walls 15 and 16 are further formed with outwardly-extending lugs or projections 19 which simulate the pivot pins or projections of the conventional large-sized jacks, to present a lifelike appearance for the toy article. Wheels 20 may be carried by the base member 11 at the ends thereof to provide the appearance of a portable or movable jack of this type. The wheels 20 may be supported on axles 21 which are carried by the base member 11, or the wheels 20 may be formed integrally with or fixed on the base member 11 in an immovable manner to merely present the appearance of wheels.

A lifting lever 22 is superimposed upon the bottom wall 12 adjacent to and spaced from the nut element 28 and is connected adjacent one end to the side walls 15 and 16 for rocking movement about an axis transversely of the side walls. Specifically, the lever 22 is pivotally mounted within the base member 11 by being pivotally engaged with the rear ends of the side walls 15 and 16. The lifting lever 22 is formed of a length of flat metal, or other suitable material, bent upon its length to the desired configuration. Preferably, the lever 22 is formed with a longitudinally-extending lever arm or lifting arm 24, which is adapted to be extended along the length of the base member 11. A depending arm 25 is fixed to or preferably formed integrally with the rear end of the lifting arm 24 and extends downwardly within the base member 11. Outwardly-extending hinge or pivot pins 26 are formed integrally with the longitudinally-extending lifting bar 24 adjacent the rear end thereof slightly forwardly of the connection of the horizontally-extending lifting bar with the vertically-extending lever arm 25. The pivot pins 26 are adapted to be rotatably extended through openings 27 formed in the opposite side walls 15 and 16 adjacent the rear, enlarged ends thereof. The openings 27 are formed adjacent the top edges of the side walls and the pins 26 are loosely engaged therein.

A nut element 28 is fixed within the base member 11 adjacent the rear end thereof. The nut element 28 is formed of a transverse plate fixed between the side walls 15 and 16 a slight dis-

tance forwardly from the rear wall 14. The plate 28 is preferably formed of such a thickness that the threads of the screw element 18 may be engaged through an opening 29 near the bottom end of the plate 28 without the addition of a separate nut to be carried by the side walls of the plate.

A screw element 18 is slidably and rotatably engaged through the opening 17 in the rear wall 14 of the base member 11, and is threadably engaged in the intermediate wall or plate 28. The screw element 18 is formed in the manner of a crank having a longitudinally-extending threaded forward screw portion 30 rotatably engaged in the rear wall 14 and nut element 28, and a crank handle portion 31 extending rearwardly on the rear side of the rear plate 14. The forward end of the screw element 18 is adapted to frictionally engage the rear side of the depending lever arm 25 to effect the pivoting movement of the lever 22 within the base member 11.

In the use and operation of the toy jack 10, with the lifting lever 24 pivoted between the side walls 15 and 16, the threaded screw element 18 engaging through the nut plate 28 and rear wall 14 will engage the depending lever arm 25 for lifting the forward end of the lifting bar 24 upon rotation of the screw element 18 to effect the forward movement within the body or base member 11. Upon threading of the screw element 18 for longitudinal movement rearwardly in the base member 11, the weight of the forwardly-extending lifting bar 24 will effect the pivoted movement of the lever 22 in a manner to lower the extreme forward end of the lifting bar 24. For further increasing this gravitational return movement of the lever 22 to its initial substantially enclosed position within the base member 11, a lifting pad 32 is fixed to or formed on the extreme forward end of the lifting arm 24. The lifting pad 32 simulates the lifting pad on conventional types of jacks which are adapted to be engaged with that portion of the member which is engaged by the jack.

I do not mean to confine myself to the exact details of construction herein disclosed, but claim all variations falling within the purview of the appended claims.

I claim:

1. A lifting toy jack comprising a bottom wall, a pair of spaced side walls positioned upon said bottom wall and secured to the latter, an end wall positioned intermediate said side walls adjacent one end of said bottom wall and secured to said bottom and side walls, an upstanding nut element positioned inwardly of and in parallel spaced relation with respect to said end wall and fixedly secured to said bottom and side walls, a longitudinally extending lifting lever superimposed upon said bottom wall adjacent to and spaced from said nut element and connected adjacent one end to said side walls for rocking movement about an axis transverse of said side walls, said lever embodying a longitudinally ex-

tending arm and second arm positioned adjacent said one end of said first-named arm and dependingly secured to the latter, an element rotatably supported in said end wall and said nut element and having one end engageable with said second arm of said lever, and hand actuatable means on the other end of said element for effecting the rotation of said element to thereby cause the rocking movement of said lever.

2. A lifting toy jack comprising a bottom wall, a pair of spaced side walls positioned upon said bottom wall and secured to the latter, an end wall positioned intermediate said side walls adjacent one end of said bottom wall and secured to said bottom and side walls, an upstanding nut element positioned inwardly of and in parallel spaced relation with respect to said end wall and fixedly secured to said bottom and side walls, a longitudinally extending lifting lever superimposed upon said bottom wall adjacent to and spaced from said nut element and connected adjacent one end to said side walls for rocking movement about an axis transverse of said side walls, an element rotatably supported in said end wall and said nut element and having one end engageable with the adjacent end of said lever, and hand actuatable means on the other end of said element for effecting the rotation of said element to thereby cause the rocking movement of said lever.

3. A lifting toy jack comprising a bottom wall, a pair of spaced side walls positioned upon said bottom wall and secured to the latter, an end wall positioned intermediate said side walls adjacent one end of said bottom wall and secured to said bottom and side walls, said end wall being provided with an aperture intermediate the ends thereof, an upstanding nut element positioned inwardly of and in parallel spaced relation with respect to said end wall and fixedly secured to said bottom and side walls, said nut element being provided with a threaded aperture, a longitudinally extending lifting lever superimposed upon said bottom wall adjacent to and spaced from said nut element and connected adjacent one end to said side walls for rocking movement about an axis transverse of said side walls, a threaded element extending loosely through the aperture in said end wall and in threaded engagement with the threaded aperture in said nut element, and having one end in engagement with said second arm of said lever, and hand actuatable means on the other end of said element for effecting the rotation of said element to thereby cause the rocking movement of said lever.
